(57) CLAIM

The ornamental design for a head wrap, as shown and described.

DESCRIPTION

FIG. 1 is a front perspective view of a head wrap;

FIG. 2 is a front view thereof;

FIG. 3 is a rear view thereof; and,

FIG. 4 is a rear view of the head wrap shown in a position of use.

The broken-line outline of the partial human figure in FIG. 4 assists in illustrating how the claimed design may appear when worn, but forms no part of the claimed design.
